CLAIM

The ornamental design for a dehumidifying, sterilizing and deodorizing machine for garments for vehicles, as shown and described.

DESCRIPTION

1. Dehumidifying, sterilizing and deodorizing machine for garments for vehicles

1.1 : Perspective

1.2 : Front

1.3 : Back

1.4 : Left

1.5 : Right

1.6 : Top

1.7 : Bottom

1.8 : Perspective
